UNITED STATES PATENT OFFICE.

GEORGE J. MURDOCK, OF BINGHAMTON, NEW YORK.

ELECTRIC-LAMP GLOBE.

SPECIFICATION forming part of Letters Patent No. 274,959, dated April 3, 1883.

Application filed August 29, 1882. (No model.)

To all whom it may concern:

Be it known that I, GEORGE J. MURDOCK, of Binghamton, in the county of Broome, in the State of New York, have invented new and useful Improvements in Carbon-Saving Globes for Electric Lamps, of which the following, taken in connection with the accompanying drawings, is a full, clear, and exact description.

This invention consists in a novel construction and combination of a transparent or opalescent globe and its attachments to an electric lamp, whereby the latter is effectually isolated from the atmospheric air, and thus the carbons of the said lamp are protected from the destructive influence of oxygen, said invention being more particularly designed for use in connection with the electric lamp for which I have now pending Letters Patent of the United States.

20 In the accompanying drawings, Figure 1 is an exterior side view of my invention. Fig. 2 is a vertical transverse section of the same, and Fig. 3 is a detached top view of the base which supports the lamp.

25 Similar letters of reference indicate corresponding parts.

A represents the electric lamp in the form of a rigid vertical skeleton frame, carrying the carbons at opposite ends and serving as electrical conductors to said carbons.

30 B denotes the base which supports the aforesaid lamp, a circular vulcanite plate or block, D, being interposed and secured to the base to isolate the lamp from the base. Concentrically around the insulating-block D is a rigid flange, b, projecting from the top of the base B, and forming an annular groove or depression, a, between said flange and insulating-block.

35 G represents a glass or other transparent or opalescent bottomless globe, having a circumferentially-reduced closed top portion or dome, G', specially fitted for the top of the lamp, for which I have now pending United States Letters Patent. The bottom portion of the globe has an inward circumferential shoulder or offset, n, by which it rests on top of the flange b of the base B. An extension of the globe from the inner edge of the offset n downward enters the groove a between the flange b and insulating-block D. By introducing in the groove a

sufficient quantity of water, oil, or other suitable liquid to immerse the foot of the globe, the same becomes hermetically sealed in its seat on the base B, and thereby effectually excludes the air from the interior of the globe.

40 C is a collar or circular band, firmly secured to the exterior of the globe immediately above the offset n thereof, and projecting downward therefrom, thus inclosing between the collar C and foot of the globe the flange b on the base B. The offset n, while forming the support for the globe, serves at the same time to brace the same to resist the inward pressure of the collar C, which is fitted closely thereto. The collar C is provided at two diametrically- 45 opposite points with two lateral extensions or lugs, r r, to the outer end of each of which is hinged a clasp, g, having on its free end a hook or shoulder, o, by which said clasp engages the under side of a lateral projecting lug, h, on the 50 side of the base B, and thus retains the said base tightly against the foot of the globe G.

45 On the lug h of the base is a flat-headed key or turn-button, k, which protrudes through a vertical slot, i, in the clasp, and when turned astride the clasp locks the latter in its before-described engagement with the lug h. Vertically through the lugs r r of the collar C pass two tubes, d d, which are firmly secured thereto, and terminate with their lower end in proximity 55 to the top of the lug h of the base B. The opposite ends of said tubes extend upward along the outside of the globe and are rigidly connected to the yoke H, which encompasses the dome G' at its junction with the main portion 60 or body of the globe G. In the tubes d slide rods f, secured to the lugs h of the base. To the side of the upper end of the rods is attached a guard or stop, s, in the form of a lug, which protrudes through a vertical slot, e, in 65 the side of the tube, said slot being closed at its lower end at such a point as to arrest the descent of the lamp when removed from the globe, as hereinafter more fully explained. I designate a bail or fork connected to the yoke 70 H, and extended over the dome G', and provided in the center of the top with a ring, L, or other suitable device for suspending the apparatus from the ceiling or other desired point.

75 E E' and F F' are binding-posts attached, 70

respectively, to the base B and yoke H, but insulated therefrom by gutta-percha collars, the upper posts being connected with the lower posts by insulated wires *l l*, which communicate with the lamp A by insulated wires *m m*, extended from the lower binding-posts through suitable channels, *c*, in the base B and block D, and connected with the base of the lamp-frame, which latter serves to conduct the electric currents to the carbons, as hereinbefore set forth. The positive current passes down the wire *l* on one side of the globe, thence through the binding-post E and the wire *m* to the lamp-frame, the negative current passing out through the other wire *m*, and thence through the binding-post E' and up the wire *l*, which connects the post E' with the binding-post F'.

The operation of my invention is as follows: When the lamp A is to be supplied with new carbons, the operator grasps with one hand the base B, which for that purpose is provided with a suitable handle, N. With the other hand he turns the key K, so as to bring the flattened head thereof in line with the slot *i* of the clasps *g*, and throws the said clasps off from the lugs *h* of the base B. This releases the said base and allows the operator to lower it, together with the lamp seated thereon, until the guard or stop *s* on the rods *f* encounters the lower end of the slot *e* of the tubes *d*, which encounter arrests the descent of the base at a point sufficiently distant from the foot of the globe to afford convenient access for manipulating the carbons of the lamp.

It will be observed that by closing the lower end of the slot *e*, as described, the danger of accidentally letting the lamp drop completely away from the globe is obviated.

The introduction of the lamp into the globe is as readily effected as its before-described removal therefrom.

Having described my invention, what I claim as new, and desire to secure by Letters Patent, is—

1. In combination with the electric lamp A, the globe G, collar C, secured to the globe, the base B, detachably connected with the collar and provided with the annular groove or depression *a*, and the insulating-block D, interposed between the base and lamp, substantially as shown and set forth.

2. In combination with the electric lamp A, the globe G, collar C, fixed to said globe, the base B, detachably connected with the collar and provided with the annular flange *b*, the insulating-block D, arranged inside of the flange with the space *a* between them, the binding-posts E E', connected to the base, and the wires *m m*, passing from said posts through the base and block D, and to the electric conductors of the inclosed lamp, substantially as specified and shown.

3. The combination, with the electric lamps A and globe G, of the yoke H, pendent tubes *d*, provided with the slot *e*, rods *f*, provided with the stop *s*, the collar C, secured to the globe and to the tubes *d*, the base B, connected to the rods *f*, the clasp *g*, the key K, and insulating-block D, all as shown and described.

4. In combination with the lamp A and globe G, the yoke H, sliding hangers *d f*, base B, insulating-block D, clasp *g*, binding-posts E E' and F F', connected, respectively, to the base and yoke, and the external conducting-wires, *l l*, and internal conducting-wires, *m m*, substantially as described and shown.

5. In combination with the lamp A, the globe G, formed with the circumferentially-contracted top portion, T, the yoke H, encompassing said top portion, the hangers *d f*, collar C, base B, and clasp *g*, substantially in the manner shown and described.

6. The combination of the base B, provided with the insulating-block D, annular flange *b*, and groove *a*, the globe G, having the offset *u*, the collar C, secured to the globe and projecting below the offset thereof and provided with the lateral extensions *r r*, and the clasp *g*, connected to said extensions, substantially as described and shown.

In testimony whereof I have hereunto signed my name and affixed my seal, in the presence of two attesting witnesses, at Binghamton, in the county of Broome, in the State of New York, this 22d day of August, 1882.

GEORGE J. MURDOCK. [L. S.]
